UNITED STATES PATENT OFFICE.

GUSTAVUS A. MONTGOMERY, OF TITUSVILLE, PENNSYLVANIA, ASSIGNOR TO TITUSVILLE FORGE CO., OF TITUSVILLE, PENNSYLVANIA, A CORPORATION OF MARYLAND.

PIPE WRENCH.

Application filed March 6, 1924. Serial No. 697,241.

This invention relates generally to improvements in wrenches but more particularly to pipe wrenches or tongs.

One of its objects is to provide a pipe wrench which is so constructed and organized that it can be conveniently manipulated in places of small compass.

Another object of the invention is to provide a reliable and efficient pipe wrench which will effectually and automatically grip the pipe when brought into engagement therewith to turn it, and which will automatically be released from such engagement when moved in a direction away from the pipe.

Further objects are the provision of a tool of this nature which is simple, strong, and durable in construction, which is not liable to get out of order, and which can be manufactured at a moderate cost.

In the accompanying drawings:

Figure 1 is a face view of the wrench in operative engagement with a pipe. Figure 2 is an enlarged sectional face view of the wrench-head. Figure 3 is a transverse vertical section on line 3-3, Fig. 2. Figure 4 is a perspective view of one of the movable gripping jaws or pawls. Figure 5 is a sectional view of a modified arrangement of mounting the movable gripping jaw in the wrench-head.

Similar characters of reference indicate corresponding parts throughout the several views.

In the preferred embodiment of the invention shown in Figs. 1-4 inclusive, 10 indicates the wrench-head or stock which may be approximately U-shape, being provided with a downwardly-facing pipe-receiving opening or recess 11 and opposing stationary jaw portions 12, 13. The latter extend or surround about three-fourths of the circumference of the pipe, the jaw 12 being curved toward its companion jaw 13 to form a contracted mouth for the opening 11, said mouth being equal to or preferably slightly larger than the diameter of the size of the pipe for which the tool is designed. Above the opening 11, the head is provided with a mortise 14 in which the lower end of a suitable handle 15 is fitted, the same being secured in place by screws 16 or similar fastenings. The jaw 12 of the wrench-head is adapted to

directly engage one side of the pipe P while the opposing jaw 13 is free from engagement therewith and constitutes a supporting arm which carries one or more retractable gripping jaws or members 17, normally extending into the wrench-opening and arranged to engage or grip the other side of said pipe.

The bearing or contact face 18 of the jaw 12 which forms a partial wall of the opening 11 is, by preference, substantially semi-circular in shape to embrace about one half the pipe and is described from the center indicated at *a*, while the remaining arcuate portion 19 of the opening-wall which is formed on the arm 13 and beyond which the gripping jaws 17 normally project for engaging the opposite side of the pipe, is described from the center indicated at *b*. As shown in Figs. 1 and 2, the radii of the arcs described from these centers are substantially the same and said centers are eccentric to each other, the center *b* being located at one side of the center *a* and below a horizontal line drawn through the latter. These radii vary for wrenches of different sizes, being approximately equal to one-half the external diameter of the pipe for which the tool is intended. In the operative position of the wrench on the pipe, shown in Fig. 1, the center *a* coincides with the axis of said pipe, so that the face 18 of the jaw 12 bears evenly against the top and adjoining side thereof, while the remaining portion 19 of the wrench-opening is eccentric to and therefore clears the opposite side of the pipe. As indicated in Fig. 2, the lower end of the gripping face 18 terminates short of a vertical line and below a horizontal line drawn through the center *a* and at a point which intersects a vertical line *c* drawn tangent to the circle described from the center *b*.

The retractable gripping jaws 17 of which two are shown in the drawings, are substantially in the form of pawls yieldingly mounted on opposite sides of the supporting arm 13 to swing into and out of the space 20, resulting from the eccentric arrangement of the portion 19 of the opening 11, for gripping engagement with the pipe P. To this end, each retractable jaw is provided at its inner end with a hub or round portion 21 seated in a correspond-

ingly-shaped socket 22 in its supporting arm and held therein by a set-screw 23 whose inner end projects into a groove 24 disposed lengthwise in the upper side of said jaw.
 5 A plunger 25 backed by a coil spring 25^a and guided in an opening 26 in the wrench-head 10 tends constantly to project each jaw firmly and positively into gripping engagement with the pipe. The downward 10 swinging movement of the jaw is limited by the lower edge thereof abutting against a stop-shoulder 27 formed on the arm-portion 13 of the wrench-head.

To allow the movable jaws 17 to be retracted clear of the space 20 to the position shown by dotted lines in Fig. 1, which action is necessary to permit the application and removal of the wrench to and from the pipe being operated upon, the arm-portion 20 13 of the wrench-head is provided in its opposite sides with escapement recesses 28 which are preferably of sufficient depth to receive the respective jaws. That portion 25 29 of each yieldable jaw below its gripping edge 30 is preferably convex, to enable the same to ride freely over the pipe when the wrench is engaged with and disengaged from it.

The retractable jaws are so positioned on 30 the wrench-head, that, when applied to a pipe for which it is designed to fit, their gripping edges 30 will positively grip the pipe at a point below its horizontal axis or below a diametral plane containing the center *a*, so that upon turning the handle 15 in the direction indicated by the arrow in Fig. 1, said jaws will bite into the pipe and cause it to turn in a corresponding direction to loosen or tighten the same. It will be noted 35 in the same figure, that the longitudinal center line of the handle is in line with the center *b* from which the arcuate portion 19 of the wrench-opening is described.

While the jaws 17 in the drawings are 40 shown as being of the same length, they may be of different lengths, if desired, whereby the grip on the pipe is distributed over the same at different radial points on its circumference and not localized on one radial line.

In applying this wrench to a pipe, its 45 opening 11 is passed over the same in a substantially upright position, the mouth of such opening being just wide enough to receive the pipe. As the wrench is thus engaged with the pipe, the yieldable jaws 17, which normally project into the wrench-opening, are at first forced or retracted into their recesses 28 by their convex lower edges 50 29 striking the surface of the pipe, as shown by dotted lines in Fig. 1. As soon as these jaws pass the upper half of the pipe they are automatically projected into gripping engagement with the pipe by their 55 spring-pressed plungers 25. In this position

of the tool, shown by full lines in Fig. 1, the same is set for turning the pipe in a clockwise direction, the arc included between the gripping faces of the jaws 12 and 17 being more than 180°. After turning 70 the wrench a fraction of a revolution to effect a corresponding movement of the pipe, the same can be turned in the reverse direction to take a new hold on the pipe, the yieldable jaws permitting a ratchet-like action for this purpose.

In removing the wrench from the pipe, the same is lifted therefrom in the direction of length of the opening 11 or in a substantially vertical direction, as shown by 80 dotted lines in Fig. 1. During this lifting or pulling movement of the tool out of engagement with the pipe, it moves bodily in a lateral direction relative to said pipe, owing to the fixed jaw-face 18 extending around 85 the lower side portion thereof, thereby causing the lower inner edge of such fixed jaw to ride on the exterior surface of the pipe and gradually forcing the movable jaws 17 against the resistance of their spring-plungers into the recesses 28. As soon as the lower edge of the fixed jaw and the lower edges of the movable jaws reach the diametral plane of the pipe, as shown by dotted lines in Fig. 1, the mouth of the wrench-opening 11 is no longer obstructed and the 90 complete removal of the wrench can be readily effected, after which said movable jaws spring back to their initial projected position.

The modification illustrated in Fig. 5, shows another way in which the movable jaws are held against lateral displacement in their sockets. In this construction, the fulcrum-end of the jaw 31 is provided with a substantially semi-circular groove 32 with 95 which a pin 33, fixed in the adjacent portion 16 of the wrench-head, is adapted to engage.

For the purpose of description, the various parts of the wrench have been located with the pipe in a horizontal position and the wrench applied thereto in a substantially upright position.

I claim as my invention:

1. A wrench of the character described, comprising a head having a pipe-receiving opening and opposing jaws, the mouth of said opening being contracted and of a size to pass over the pipe to be turned while its body portion is of such dimensions as to permit a lateral movement of the wrench relative to the pipe, one of said jaws extending around one side of the pipe and having its bearing face concentric therewith, the other jaw having its opposing face eccentric to the pipe and in spaced relation thereto, and a releasable gripping member fulcrumed on said last-named jaw and normally projecting into said head-opening for engagement with the other side 130

of the pipe, said gripping member being arranged to grip the pipe when the wrench is turned but permitted to be released therefrom when the wrench is pulled in a direction away from the pipe, or to be automatically displaced from the opening-mouth when the wrench is thrust over the pipe.

2. A wrench of the character described, comprising a head having a downwardly-facing pipe-receiving opening and opposing jaws adapted to extend around approximately three-fourths of the circumference of the pipe, the mouth of said opening being contracted and of a size to pass over the pipe, the opposing faces of said jaws being curved, one face engaging substantially one half the pipe and being concentric therewith, the other face being free from engagement with the pipe and eccentric thereto, the face of the jaw engaging the pipe terminating at a point below the horizontal axis thereof and substantially on a vertical line tangent to the opposite side of the circle on which the eccentric face of the other jaw is described, and a retractable gripping member mounted on said last-named jaw for movement into and out of said opening and arranged to grip the pipe at a point opposite the companion jaw.
3. A tool of the character described, comprising a handle, an open-ended wrench-head connected therewith having opposing jaws, one of the jaws being adapted for engagement with one side of an object to be turned while the other is free from engagement therewith, said last-named jaw having a socket and a recess therein, a retractable gripping member for engaging the opposite side of the object fulcrumed in said socket and movable into and out of said recess, the fulcrum end of said gripping member having a groove in its periphery, and a pin secured to said wrench-head and extending

into said socket for engagement with the groove of said gripping member.

4. A tool of the character described, comprising a head having a pipe-receiving opening and opposing fixed jaws, one of the jaws being curved inwardly toward the other jaw to form a contracted mouth, the latter being of a size to pass over the pipe and the body of said opening being larger than the pipe to permit a lateral movement of the wrench-head relative to the pipe, and a gripping member mounted on said last-named jaw for movement relative thereto and normally extending part-way across said mouth with its gripping portion facing in a direction toward the closed end of the pipe receiving opening, said gripping member being displaceable from such opening by contact with the pipe during the application and removal of the wrench to and from the same.

5. A tool of the character described, comprising a handle, an open-ended wrench-head connected therewith having stationary jaws facing in a direction opposite to that of said handle, one of the jaws being arranged to bear against one side of an object to be turned while the other is free from engagement therewith and eccentrically disposed relatively thereto to permit a lateral displacement of the wrench relative to the object, and a retractable gripping member applied to the eccentrically-disposed jaw and normally extending into the wrench-opening for engagement with the opposite side of the object, said gripping member being automatically displaceable from said opening by the lateral movement of the wrench-head relative to the object, such movement being effected by the application and removal of the wrench to and from the object.

GUSTAVUS A. MONTGOMERY.
